UNITED STATES PATENT OFFICE.

OLAF ANDERSON, OF ERSKINE, MINNESOTA.

BAG-HOLDEE.

1,081,291.

Specification of Letters Patent.

Patented Dec. 16, 1913.

Application filed June 9, 1913. Serial No. 772,687.

To all whom it may concern:

Be it known that I, OLAF ANDERSON, a citizen of the United States, residing at Erskine, in the county of Polk and State of Minnesota, have invented certain new and useful Improvements in Bag-Holders, of which the following is a specification.

This invention relates to improvements in bag holders and its object is to produce a device of this class that is simple in construction and operation.

The invention consists in the combination and arrangement of parts to be hereinafter fully described in the following specification, pointed out in the claims and illustrated in the accompanying drawing which forms a part of said specification and in which—

Figure 1 is a view of my improved bag holder, partly in section, holding a bag shown in section. Fig. 2 is a side view of the bag holder in use, a portion of the legs and of the bag being broken away. Fig. 3 is a view similar to Fig. 2 with the movable parts in an altered position.

Like reference characters indicate corresponding parts throughout the several views.

1 is the cone of my bag holder formed with a flared mouth 2 and with a bulged annular base 3 and provided with legs 3^a. To the cone 1 a plurality of ears 4 are secured each of which carries pivotally a clamp 5 formed with a recessed portion as 6 near its free termination and with an angular slot 7. The recessed portion of the clamp is adapted to fit over and engage the annular base of the cone 1 when in operative position.

To the cone 1 a plurality of springs 8 are secured as at 9 in the plane of the ears 4 and said springs extend beyond the lower termination of the cone 1 and are provided near their free extremities with lugs 10 designed to abut the bulged annular base of said cone and retained in frictional contact therewith by said spring; each spring 8 is formed with a slot 11 in the plane of the slots 7 of the clamps and a movable ring 12 provided with handles 13 encircles the cone 1, each of said handles 13 being provided with a screw 14 that is slidably disposed in the slotted portion 11 of the springs 8; said ring 12 is further provided with lugs 15 provided with bolts 16 disposed in the slotted portions 7 of the clamps 5.

Operation: When the ring 12 is manually moved toward the flared mouth 2 of the bag holder the screws 14 ride to the end of the slots 11 adjacent that mouth and the bolts 16 ride to the end of the angular slots 7 adjacent that mouth, the said belts having the effect of forcing the clamps 5 out of engagement with the bulged annular base of said cone and the screws 14 permitting the lugs 10 of the springs 8 to be manually forced away from the said bulged base. The mouth 65 of the bag 17 to be held is now passed over the said annular cone base and the ring 12 forced away from the mouth 2 of the cone into operative position causing the clamps 5 and springs 8 to press the mouth of the 70 bag 17 against the bulged annular base 3 of the cone retaining the bag in open position. To remove the bag the ring 12 is, of course, moved into inoperative position and the bag withdrawn from the cone.

What is claimed is:—

1. In a bag holder, a cone formed with a bulged annular base and suitably supported, clamps pivotally secured to said cone and provided with angular slots, slotted springs 80 secured to said cone, a ring disposed about said cone and provided with means for slidably engaging the slotted portions of said clamps and springs, and lugs formed integral with said springs. 85

2. In a bag holder, a cone formed with a bulged annular base and suitably supported, clamps pivotally secured to said cone and provided with angular slots and recessed terminations for engagement with the said 90 bulged annular base, springs secured to said cone and slotted in the plane of the slotted portions of said clamps, a ring disposed about said cone and provided with means for slidably engaging the slotted portions 95 of said clamps and springs, and lugs formed integral with said springs.

In testimony that I claim the foregoing as my own I have hereto affixed my signature in the presence of two subscribing witnesses. 100

OLAF ANDERSON.
